Primary Examiner — Cynthia Ramirez*Assistant Examiner* — Llorellys Martinez-Rivera(74) *Attorney, Agent, or Firm* — Zollinger & Burleson Ltd.(57) **CLAIM**

The ornamental design for a window component extrusion, as shown and described.

DESCRIPTION

FIG. 1 is a top perspective view of a window component extrusion showing our new design; and,

FIG. 2 is a bottom perspective view of the window component extrusion in FIG. 1.

The window component extrusion is shown with a symbolic break in its length. The appearance of any portion of the window component extrusion between the break lines forms no part of the claimed design.
